G. A. FANDREY,
RECORD CLEANER FOR SOUND REPRODUCING MACHINES,
APPLICATION FILED OCT. 20, 1919.

1,354,386.

Patented Sept. 28, 1920.

UNITED STATES PATENT OFFICE.

GUSTAV AUGUST FANDREY, OF CEDAR RAPIDS, IOWA.

RECORD-CLEANER FOR SOUND-REPRODUCING MACHINES.

1,354,386.

Specification of Letters Patent. Patented Sept. 28, 1920.

Application filed October 20, 1919. Serial No. 331,805.

To all whom it may concern:

Be it known that I, GUSTAV AUGUST FANDREY, a citizen of the United States, residing at Cedar Rapids, in the county of Linn and 5 State of Iowa, have invented certain new and useful Improvements in Record-Cleaners for Sound-Reproducing Machines; and I do declare the following to be a full, clear, and exact description of the invention, such 10 as will enable others skilled in the art to which it appertains to make and use the same.

This invention relates to record cleaners for sound producing machines, and it relates 15 more specifically to an improved reproducer attachment for brushing dust and other foreign matter from the record while the machine is in use.

One object of this invention is to provide 20 an improved record brushing attachment for quickly and easily attaching to a Columbia graphophone or other sound reproducing machine without the necessity of changing or preparing the machine for receiving it.

25 Another object is to provide an attachment of this character which is adjustable to different positions or different angles with respect to the reproducer and record.

A further object is to provide a device of 30 this character with an improved attaching element which is formed of a single piece of light spring wire and can be manufactured at an exceedingly low cost.

Other objects and advantages may become 35 apparent to persons who read the following details of description in connection with the accompanying drawings, in which:—

Figure 1 is a front elevation of a graphophone reproducer having my improved record brushing device attached thereto, the record being indicated in section.

Fig. 2 is a view showing the reproducer and record in vertical section along the line 2—2 of Fig. 1, my improved brushing attachment being illustrated in side elevation.

Fig. 3 is a perspective view of the record brushing attachment detached.

Fig. 4 is a vertical sectional view substantially along the line 4—4 of Fig. 3.

Fig. 5 is a detail view illustrating a slightly modified form of brush.

Referring to these drawings in detail, in which similar reference characters correspond with similar parts throughout the 55 several views, and in which the reproducer

and record are generally indicated by the reference characters 5 and 6:

My improved attaching device comprises a length of spring wire formed with a brush holding end portion 7, reproducer-engaging elements 8 and 9, a bowed bar or spring 10 between the laterally extending loops or reproducer-engaging elements 8 and 9, and an upward extension or manipulative element 11, the latter being preferably curved and terminating in an auxiliary reproducer-engaging element 12.

Moreover, this invention comprises a brush which is formed of bristles or fibers 13 which are clamped between the adjacent surfaces of a brush-head 14. This brush head is preferably formed of a sheet metal blank which is apertured at 15 and 16, and which is folded upon itself along a line passing through the apertures 15 and 16. The end 75 portion 7 of the wire or attaching element extends inward through the aperture 16, thence along the clamping plate or head 14 to and through the aperture 15, and its extreme end portion may be bent down upon 80 the top edge of the head 14 as shown at 14^a in Fig. 5. The part of the end portion 7 between the apertures 15 and 16 may be slightly bowed downward, as indicated at 85 17 so that there can be no movement of the brush relative to the attaching element or spring wire.

It is to be understood that this device is designed for attachment to such reproducers as illustrated, in which the diaphragm is 90 held in place by means of a rim or flange such as indicated at 5' in Fig. 2, that the distance between the attaching elements 8 and 9 is slightly greater than the internal diameter of the flange 5' when the device is 95 detached, and that when the bowed spring or bar 10 is bowed to a greater extent than normally, the attaching elements 8 and 9 are brought sufficiently close together to be seated against the inner surface of the flange 100 5' as illustrated. It is also to be understood that the spring pressure of the bearing 10 holds the engaging elements 8 and 9 firmly against their seats within the rim 5, so that the brush is substantially stationary with relation to the reproducer and record. It is obvious that by pressing downward on the manipulative element 11, the device may be 105 quickly and easily disengaged from the reproducer, and that it may be as quickly and 110

easily replaced in the position shown or at any other desired angle with relation to the reproducer and record. Although the device would be practical and efficient without the auxiliary engaging element 12, the latter renders the device more secure in its different adjustments, that is, by effectually preventing the device from turning on a longitudinal axis.

- 10 It will be seen that the manipulative element 11 and brush holding element 7 act as stops to prevent the engaging elements 8 and 9 from being pushed into contact with the diaphragm and endangering the same.
- 15 From the foregoing description, it will be seen that this device is not only practical and convenient, but that it may be manufactured at a very low cost.

Although I have described this embodiment of my invention very specifically, it is not intended to limit this invention to the exact details of construction and arrangement of parts, but changes may be made within the scope of the inventive idea as described and claimed herein.

What I claim as my invention is:

1. In a record cleaner attachable to a reproducer of a sound reproducing machine, a brush carrying attachment, a pair of reproducer-engaging elements, and a spring connecting said reproducer-engaging elements and adapted to press them away from one another to a distance slightly greater

than the internal diameter of the dia- 35 phragm-holding flange of the reproducer, whereby the said reproducer-engaging elements may have spring-pressed engagement with the internal surface of said flange.

2. In a record cleaner attachable to a reproducer of a sound-reproducing machine, 40 a brush-carrying attachment comprising a bowed spring bar formed with reproducer-engaging elements adapted to be seated on the inner surface of the flange that holds the diaphragm in place, said bar being effective to press said reproducer-engaging elements against said inner surface and thereby hold itself in engagement with the reproducer.

3. A brush-carrying attachment for a 50 sound reproducing machine, formed of a single piece of spring wire and comprising a brush-holding element, a pair of laterally extending attaching loops, a bowed spring portion between the attaching loops, and a 55 manipulative loop, said attaching loops being disposed between said brush-holding element and manipulative loop, said brush-holding element and manipulative loop also constituting stops to limit attaching movement of the attachment.

In testimony whereof I have hereunto set my hand.

GUSTAV AUGUST FANDREY.

Witness:

C. W. BINGHAM.
